UNITED STATES PATENT OFFICE

2,488,063

BANK VAULT DOOR AND FRAME

Loyal M. Massie, Hamilton, Ohio

Application December 27, 1945, Serial No. 637,326

4 Claims. (Cl. 109—64)

1

This invention relates to bank vault doors and frames, and the object thereof is to provide a novel construction which is stronger and cheaper than the old style doors and which does away with the pressure bar system and hinges now employed.

Another object of the invention is to provide a door which is supported on rollers to move easily, and provided with means for releasing the latch bolts thereof and for sliding the door to an open or closed position by means of a motor controlled by a switch to be readily operated and thereby avoid manually moving heavy bank doors.

Another object of the invention is to provide a door which is extremely safe against unwarranted entry into a vault or the like, and which is provided with means for guiding the same in its movements.

Another object of the invention is to provide guides for the door which also provide a rack adapted to be moved back and forth for opening and closing the door in connection with a power driven gear to open and close the door silently and efficiently.

Other objects and advantages reside in the details of construction and operation as more fully hereinafter described and claimed, reference being had to the accompanying drawings forming part hereof, wherein like numerals refer to like parts throughout, and in which:

Figure 1 is a front elevation of a vault equipped with a door and frame in accordance with the invention.

Figure 2 is a vertical sectional view taken on the line 2—2 of Figure 3.

Figure 3 is an enlarged vertical sectional view taken on the line 3—3 of Figure 2.

Figure 4 is a fragmentary horizontal sectional view enlarged, taken on the line 4—4 of Figure 2.

Figure 5 is a vertical sectional view taken on the line 5—5 of Figure 2.

Figure 6 is a horizontal fragmentary sectional view taken on the line 6—6 of Figure 2.

Figure 7 is a perspective view partly broken away of one of the door bolts or latches.

Figure 8 is a perspective view of one of the engaging members of the bolts.

Figure 9 is a perspective view of a portion of the bottom frame of the door showing the guides and roller seats for the door.

Figure 10 is a fragmentary perspective view of a portion of the bottom of a door showing the rack bars thereon.

Figure 11 is an enlarged fragmentary vertical sectional view taken through the sliding door sec-

tion and frame and showing the door operating means.

Figure 12 is a fragmentary perspective view of the upper portion of the sliding door section, and

Figure 13 is a longitudinal sectional view of the structure shown in Figure 11.

Referring to the drawings in detail, in which like reference characters designate corresponding parts throughout the several views, the numeral 10 designates the vault wall, which may be of concrete reinforced, or other suitable construction of sufficient strength customary in devices of this character. This wall is provided with the opening 11 adapted to receive the embedded reinforced frame 12 entirely around the same, including the sides, top and bottom. The bottom and top are provided with grooves 13 designed to receive spaced parallel guide flanges 14 at the edges of the door 15 including a slidable section 16 to move into and out of a hollow stationary wall section 17 cooperating with vault wall 10, which sliding section 16 is provided at one end with a dove-tailed formation including triangular portions or strips 18 forming gibbs tapering or beveled inwardly toward the opposite surfaces of the door. This end is designed to engage within the inner end of hollow stationary section 17 and the other end engages one end of the door opening 11 and forms stops for this purpose. The door section 16 comprises inner and outer plates 19 and 20 and sliding section 16 may be provided with a fire-proof filler 21 therebetween, while the stationary hollow section 17 may be beveled on the inner side at the inner end thereof, as indicated at 22 with a corresponding beveled formation at the end of the door section 17. The top and bottom edges of the door section 16 may be reinforced by a strip 23 preferably of metal, having the spaced guides or flanges 14 projecting therefrom to enter the corresponding grooves 13 of the frame 12. The dove-tailed end or the strips 18 are provided at the inner end of the movable door section 16 to engage portions 22 to provide a tight joint therebetween, and the top of section 16 is also beveled to connect the top of the sliding door section to the vault wall or frame 12 thereof, as more particularly shown in Figure 5 of the drawings. The door frame 12 is made up of four sections connected in interfitting relation at the corners, and welded at 24, thus permitting convenient assembly thereof. This permits the frame and door to be prefabricated in the plant and installed in the wall, which may be formed to receive the same or may be built around the frame with the door sections

in position. These joints may be of the tongue and groove type, in which certain of the sections are provided with tenons or reduced central extensions at the ends thereof, as indicated at 25 to enter corresponding mortises or central grooves 26 in the ends of the connected sections, said parts being apertured transversely in alignment as indicated at 27 to connect the same by bolts or pins 28, thus facilitating the assembly of the frame and the mounting thereof in position. Of course, the opposite ends of the pins 28 may be headed in the manner of rivets, the construction being such that by upsetting the ends thereof, it is impossible to take the frame apart without cutting the rivets and therefore, access through the door opening at the frame is prevented.

The bottom frame member is provided in its top surface with the guide-ways or grooves 13 slidably engaged by said flanges 14 and centrally and longitudinally therebetween, with pockets or spaced transverse semi-circular recesses 29 designed to receive anti-friction rollers 30 on which the door section 16 is adapted to move easily and with the least amount of friction, so as to greatly facilitate the opening and closing thereof. In addition, the flanges 14 on the bottom edge of the door section 16, are provided with longitudinal series of rack teeth 31, extending throughout the length of said movable door section and adapted to be engaged by gears or pinions 32 fixed to a horizontal drive shaft 33 mounted in a recess 34 in the floor 35 or the bottom frame member 12. This shaft extends into an opening 36 provided in the floor, in which is mounted a suitably controlled motor 37 preferably of the electric type, the rotor of which has the shaft 33 extending therefrom and may be suitably controlled at any desired point, or at the motor, to rotate said shaft and thereby correspondingly rotate the gears 32 to impart opening and closing or reciprocating movements to the movable door section. Thus, in addition to the door section 16 being supported on the rollers 30 for movement back and forth with the least amount of friction, it is operated by power from the motor, thereby eliminating manual operation of heavy doors such as used in bank vaults and the like.

In order to lock the slidable door section 16 in closed position, two oppositely extending bars 38 are provided, the same having reduced end portions 39 provided with rack gears 40 and guided up and down by means of pins 41 entering slots 42 in the bars 38, said pins being mounted on the inner wall 19. The rack bars 40 engage a pinion 43 having a shaft 44 extending to the outside or front of the door, as indicated more particularly in Figure 3 of the drawings and provided with a removable operating handle 45 for actuating the same. The bars 38 are of T-shaped formation and disposed in reversed position with the heads 46 thereof disposed near the top and bottom edges of the door. The ends of the heads 46 are slotted or bifurcated as indicated at 47 and have bolts 48 pivoted therein through the medium of reduced extensions 49, the furcations of the ends of the head 46 being apertured and likewise the ends 49, as shown at 50 and 51, to pivotally connect the bolts 48 to the heads 46 as indicated at 52. The bolts are designed to enter recesses or keepers 53 in the top and bottom portions of the frame 12, and may be operated or held by a time mechanism operated by dials 54 at the front of the movable door section 16. By this means, only a person knowing the combina-

tion can actuate the release or the locking mechanism which bolts the door in closed position.

It will thus be seen that the door and frame can be cheaply manufactured in prefabricated form and that with the door sections when mounted as described the slidable section 16 will move easily, in addition to being capable of operation by power merely by switching on the operating or driving motor 37. In this way, all hinge construction as well as the pressure bar system usually employed in connection with heavy bank doors, is entirely dispensed with. The rollers form anti-friction means and take the place of hinges and the guides serve in connection with the pinions as a rack on the bottom section of the slidable door section 16 so that the door can be opened and closed easily by the motor. This will mean that a motor of very small capacity or horsepower may be used. Also, all joints may be welded for additional strength. Moreover, only two actuating bars for four bolts are necessary, whereas the old style hinge doors have from twenty to twenty-four bolts which must be mounted and which do not give any additional strength or safety to the doors. Besides, the hinged doors must swing outward, taking up valuable space, whereas the present slidable door will disappear in the frame and will need no extra room for its operation.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

What I claim is:

1. In a bank vault, a vault wall having an opening, a frame embedded in the vault wall around the opening and forming a door opening, said frame having guide-ways, a door having guides slidably engaged in said guide-ways, a hollow stationary wall section mounted in the frame, 45 said sliding door section being movable into and out of said stationary wall section, and tapered gibs mounted on opposite sides of the door at its inner edge and engageable with the inner surfaces of the stationary wall section when the door is closed.

2. In a bank vault, a vault wall having an opening, a frame embedded in the vault wall around the opening and forming a door opening, said frame having guide-ways, a door having 50 guides movably engaged in said guide-ways, said door comprising spaced plates and a fire-proof filling therebetween, strips along the top and bottom edges of the door having the guides formed thereon, and a stationary wall section mounted in the frame and forming a hollow space to receive the door therein when open.

3. In a bank vault, a wall having an opening therein and an inner extension extending half-way across the opening, a sectional frame around 55 the opening, a stationary door section in the frame and opening spaced from the extension of the vault wall and forming a space therebetween having oppositely beveled inner faces at the inner ends thereof vertically of the opening forming a 60 restricted passage, a movable door section having

opposite tapered extensions engageable with said beveled portions and movable into the space between the wall and stationary section when open and adapted to be limited in the closing movement by engagement of said tapered portions with the beveled portions of the wall and stationary section, and guiding means at the top and bottom of the frame and movable section interfitting between the movable section and frame.

4. In a bank vault, a wall having an opening 10 therein and an inner extension extending half-way across the opening, a sectional frame around the opening, a stationary door section in the frame and opening spaced from the extension of the vault wall and forming a space therebetween 15 having oppositely beveled inner faces at the inner ends thereof vertically of the opening forming a restricted passage, a movable door section having opposite tapered extensions engageable with said beveled portions and movable into the space 20 between the wall and stationary section when open and adapted to be limited in the closing movement by engagement of said tapered portions with the beveled portions of the wall and

stationary section, guiding means at the top and bottom of the frame and movable section interfitting between the movable section and frame, rollers mounted at the bottom of the frame, said movable section being movable along said rollers, and means engaging the bottom of the movable section to open and close the same.
